UNITED STATES PATENT OFFICE

CHARLES LADD NORTON, JR., OF BOSTON, MASSACHUSETTS

FURNACE

Application filed February 8, 1929. Serial No. 338,567.

Chemical and physical laboratories, small-scale metallurgical operations, often require furnaces capable of developing and maintaining high temperatures. Small electric furnaces supply this requirement, but are wasteful of heat and costly to operate in proportion to the thermal values obtained; gas heated furnaces of the general type indicated are capable of developing and maintaining high temperatures, of the order of 2500° F. only when operated by blowpipe burners by which such temperatures can be maintained only with difficulty and with large liability to failure.

One factor of difficulty is the large surface of the furnace chamber itself as compared with the volume thereof. Thermal energy developed in the small volume of the chamber is dissipated by conduction through the walls of the chamber, especially as the conductivity of the wall-material rises with temperature-differential, and by the successively rapid translation of hot gases through and out of the furnace. Other factors of difficulty and detriment are the inability of furnace wall-material to endure stresses due to local expansions and contractions. The objects of my invention are, to provide a furnace-structure of small volume, adapted to the purposes above indicated, in which, with an ordinary Bunsen type burner, temperatures as high as 2600° F. can be quickly attained and economically maintained with the burner operating under normal draft, and which can provide maintained temperatures between 2850° and 3100° F. if the burner be worked under forced draft.

These objects I have attained by the small-furnace structure which exemplifies my invention, in which the material of the furnace wall is composed of such material and has such a minutely divided and distributed cell-structure that its coefficient of conductivity at 2000° F. is of the order of 3.1 (B. t. u., per square foot, per inch thickness, per degree F. temperature differential, per hour). In general outlines, a small-capacity furnace exemplifying my invention is illustrated in the drawings hereto annexed, in which

Fig. 1 shows such a furnace in vertical mid-section;

Fig. 2, the furnace chamber block, in top plan view;

Fig. 3 shows an alternative form of furnace body, in vertical mid-section;

Fig. 4 shows a top plan view of the same; and

Fig. 5 shows, in vertical mid-section, a modified form.

The body-portion, 1, of the furnace, here shown, consists of a refractory, low conductivity block of brick material, characterized by cellular structure. The external shape of this block may be as desired, the cylindrical form shown is compact and convenient.

The furnace chamber is formed in this block preferably by boring it out of an originally plane-ended shape.

Thus, I take a preformed cylindrical block 1, of such refractory cellular brick material and, with a boring tool bore the main chamber 2, down to a ledge 3, which will serve to support a refractory-material ring 10, for holding a crucible or the like, shown in dotted lines at 11. From the ledge 3, a smaller and conical or conoidal tool is used to make a tapering bore down to the point 4, from which a straight cylindrical hole 5 is bored through the lower surface of the block.

To cover the furnace block, I provide a block 7 of similar material, centrally bored into its body at 8, and transversely bored at 9. A draught-stack of suitable height will preferably be provided to maintain upward draught from the passages in the cover block.

The aperture 5 in the furnace block is of such diameter as to admit the delivery end of a Bunsen type gas burner, preferably leaving an annular space between the burner tube and the wall of the aperture 5, for admission of auxiliary air to the burner flame.

In Figs. 3 and 4, there is illustrated an alternative form of furnace body, in this case made of two blocks of refractory insulating material, 1^a, 1^a, which meet at 1^b; the furnace chamber is bored half in one block and half in the other, the parts 2^a, 2^a; 3^a, 3^a; 4^a, 4^a, and

5^a, 5^a, forming a chamber, when the two blocks are matched together, similar to that shown in Figs. 1 and 2. A frame 12, shaped to slip over the juxtaposed blocks 1^a, 1^a, 5 (here shown as rectangular) serves to keep them in proper assemblage for operation.

In Fig. 5, there is shown a modified form of furnace, in which the body 1 is as shown in Fig. 1, wherein the cover 7^a is molded or 10 bored so as to form a bridge 21 of oval section, on either side of which are provided flues 22, 22, which meet at the top of the cover in a vent 23, which should be connected to a suitable stack.

15 Whether this, or the cover form shown in Fig. 1, be used, the arrangement is such that, with respect to the crucible or other object, 11, to be heated, the furnace chamber is on all sides closed against free radiation to the 20 outside of the apparatus.

As to the structure of the furnace-block itself: This is of refractory material, containing in its total volume as large a proportion 25 of cellular voids as is consistent with mechanical strength, these voids of small dimensions, uniform in dimension and uniformly distributed. This type of structure affords high heat insulating properties to the block as a whole, and this property is important for the purposes of this invention, especially at and near the walls of the furnace cavity, because there, high insulating value 30 operates to maintain high surface temperature.

35 The material which I have found best adapted to secure these results is kaolin brick, made by frothing a mixture of ground kaolin, some ground kaolin grog, wood flour, and water, either by beating it mechanically 40 or blowing air into it, depositing the froth when freshly made, into a mold, filtering off surplus water immediately, with attendant shrinkage of the froth, thus stiffening the walls of the air bubbles, initially nucleated on the wood flour so that the froth becomes stable and its bubbles no longer break; then drying, and afterward burning the 45 brick shapes under regulated conditions which include maintenance of a reducing atmosphere in the kiln which prevents too rapid increase of temperature which would occur if the conditions permitted the included wood flour to burn, retarding the rate of 50 temperature increase within the range where- 55 in kaolin-included water is driven off, and finally allowing the wood flour residues to burn out in an oxidizing atmosphere; and lastly, allowing the brick to cool slowly. The 60 product is a heat-refractory brick which serves in its permanent form the froth-structure of the fluid starting-material; the volume of the brick as a whole consists largely of minute voids or cells, all substantially of the same order of magnitude, uniformly distributed; the solid material of the brick is dis-

tributed with corresponding uniformity between the cells as thin cell-walls.

The brick thus made, volume for volume, 70 has a weight not more than one-sixth that of the burned kaolin material, because of the inclusion therein of gas (air) filled voids; the voids themselves are very small, 0.01 inch and less, almost if not quite microscopic voids predominating; they are uniformly distributed through the brick; the partitions of 75 burned brick material surrounding the voids are consequently very thin and therefore offer small areas to heat transmission, and moreover impart capacity for internal yielding and accommodation to stresses produced by temperature differentials, and therefore the brick are not liable to rupture.

The conductivity coefficient of such brick 80 is graded from the order of 1.5 B. t. u. per square foot area, per one inch thickness, per 85 1° F., per hour, at 400° F., to the order of 3.0 B. t. u. per square foot area, per one inch thickness, per 1° F., per hour, at 2000° F.

A furnace made as above described operates as follows: The crucible, 10, or other object to be heated, being placed in the chamber 2, and the cover block 7 laid over the furnace block, the blocks being placed on any suitable stand or support (not shown in the drawings), an ignited Bunsen type burner is 90 inserted in the lower opening in the furnace block. The burning gas mixture presently raises the temperature of the surface of brick material on the surface of the chamber wall to incandescence; the high heat-insulating property of the cellular structure immediately back of the exposed chamber wall enables the gas flame to bring the surface to such temperature. Thereupon the action of 95 the surface of solid incandescent material on the mixture of unconsumed combustible gas and auxiliary air supplied through the annular clearance around the tip of the burner 6, establishes vigorous combustion, accelerates the temperature rise in the chamber 100 and maintains it accordingly. With a Bunsen type burner operating under its normal draft, the temperature in a small furnace of this character quickly attains and continues 105 at 2600° F. Forced draft, putting the burner in blowpipe action will raise this temperature to the neighborhood of 3100° F. In either condition of draft, the gas consumption 110 is economical. Under normal burner draft, the furnace operates almost noiselessly. So far as I am informed, temperatures of the stated order have not been attainable in 115 furnaces of the class designated, except in those of the electrically heated type, which 120 are of high first cost, and relatively costly to operate.

125 Since furnaces of the type designated are universally used to operate on fusible materials of relatively high heat conductivity 130

and are therefore contained in crucibles which, though necessarily refractory, are of as high thermal conductivity as is practicable, any object to be heated in such furnace as embodies the above described improved characteristics, will absorb heat into its body and rise in temperature much more slowly than the surface of the furnace chamber wall of my above described improved furnace. 5 Stated conversely: The surface of the furnace chamber wall will rise in temperature, from initiation of combustion to the point of equilibrium, well above 2000° F., far more rapidly than the surface of the object to be 10 heated; consequently the attainment by such object of the temperature at which equilibrium is reached is very rapid, and the temperature of equilibrium very high, materially higher than has heretofore been attainable in gas-furnaces under like conditions of combustion.

As to durability, a furnace constructed according to these specifications has without injury endured one hundred and more successive heats, under the high temperatures above stated, whereas furnaces of the small-dimensioned type heretofore made or obtainable, are seriously deteriorated or destroyed after not more than twenty (and usually much fewer) heats to the highest temperatures obtainable in them, which are substantially lower than those obtainable in the improved furnace herein described.

I claim:

35 1. A fuel fired furnace comprising upper and lower blocks of refractory material, the lower block having a substantially vertical passage diverging upwardly from a point adjacent the lower end thereof to an enlarged 40 portion providing a working chamber in the upper end of the passage, the upper block being adapted to rest on the lower block and having a passage providing a flue extending from the working chamber through this 45 upper block to the atmosphere, this upper block having refractory material spanning the upper end of the working chamber for retaining heat therein.

2. A fuel fired furnace comprising separable upper and lower blocks of refractory material, the lower block having a substantially vertical passage extending therethrough, this passage diverging upwardly from a point adjacent the lower end thereof to an enlarged portion forming a working chamber at the upper end of the passage, the upper block being adapted to rest on the lower block and to extend across the upper end of the working chamber, this upper block 55 having a substantially horizontal passage extending therethrough and having an opening from its under side to this passage, this opening being smaller than the upper end of the working chamber so that refractory material 60 about the opening may overlie the working 65

chamber for retaining heat therein when the opening is approximately centered over the working chamber and the opening and the substantially horizontal passage may provide a flue for conducting gases from the 70 working chamber.

3. A fuel fired furnace comprising separable upper and lower blocks of refractory material, the lower block having a substantially vertical passage extending therethrough, this passage diverging upwardly from a point adjacent the lower end thereof to an enlarged portion forming a working chamber at the upper end of the passage, the upper block being adapted to rest on the 75 lower block and to extend across the upper end of the working chamber, this upper block having passages extending from the working chamber outwardly away from each other and then inwardly toward each other, and 80 coming together substantially at the upper surface of the upper block to provide a flue for escape of gases from the working chamber, the refractory material between the passages forming a bridgepiece extending across 85 the upper end of the working chamber for retaining heat in the latter and for avoiding radiation losses.

4. A fuel fired furnace comprising upper and lower blocks of refractory material, the 90 lower block having a substantially vertical passage diverging upwardly from a point adjacent the lower end thereof to an enlarged portion providing a working chamber in the upper end of the passage, the upper block 95 being adapted to rest on the lower block and having a passage providing a flue extending from the working chamber through this upper block to the atmosphere, this upper block having refractory material spanning 100 the upper end of the working chamber for retaining heat therein, the material forming the working chamber wall being of low thermal conductivity having voids separated by thin membranes, the surface membranes 105 of the chamber becoming almost instantaneously radiant upon heating whereby heat input is rendered substantially immediately available as usable radiant heat in the furnace chamber.

Signed by me at Boston, Massachusetts this 110 fifth day of February 1929.
